Primary Examiner — Cynthia M. Chin(74) *Attorney, Agent, or Firm* — Plumsea Law Group,
LLC(57) **CLAIM**

The ornamental design for a construction set tool, as shown and described.

DESCRIPTION

FIG. 1 is a top front isometric perspective view of a construction set tool showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The broken lines and unshaded areas are included to identify parts of the article's appearance that form no part of the claimed design. The various directional adjectives used in this specification, such as “front,” “rear,” “side,” “top,” and “bottom,” refer to the construction set tool as illustrated.
